UNITED STATES PATENT OFFICE.

WILLIAM WILD, OF BLACKPOOL, ENGLAND, ASSIGNOR OF ONE-HALF TO WEST'S GAS IMPROVEMENT COMPANY LIMITED, OF MANCHESTER, LANCASTER, ENGLAND.

CHARGER FOR RETORTS.

1,386,919.

Specification of Letters Patent.

Patented Aug. 9, 1921.

Application filed March 26, 1919. Serial No. 285,171.

To all whom it may concern:

Be it known that I, WILLIAM WILD, a subject of the King of Great Britain and Ireland, and resident of Beechwood, Newton 5 Drive, Blackpool, in the county of Lancaster, England, have invented certain new and useful Improvements Relating to Chargers for Retorts, of which the following is a specification.

10 This invention relates to the charging of retorts or chambers (hereinafter termed retorts) of the horizontal or inclined type for the destructive distillation of carbonaceous materials, and refers particularly to such retorts when adapted for continuous working, the material being fed into one end of the retort intermittently and causing an equivalent quantity of carbonized material to be discharged from the other end of the retort. 15

20 By investigation and experiment, I have found that it is essential that the quantity of coal or the like which is being fed into the retort must be placed between the coal being carbonized and the feeding plunger or ram 25 in such a manner that the said plunger shall act upon a layer of coal which fills the space between itself and the carbonizing material, so that there is an even propulsive effort over practically the whole face of the material 30 in the retort; binding or wedging of the charge is thereby obviated.

My invention comprises the employment for charging horizontal or inclined retorts of the continuously operating type, of a ram 35 or plunger consisting of at least two parts (forming a main ram and an auxiliary ram respectively) one of which serves to propel the material, constituting a charge, into a position in which it fills the space between 40 the other part and the coal or the like being carbonized in the retort, when the ram or plunger advances as a whole to feed the charge into the retort.

45 My invention further comprises the employment of a ram or plunger made in two parts, one of which is directly connected to the power actuating means, while the other part is propelled from the former when the two parts have their acting faces in line 50 with one another.

My invention further comprises the provision of an automatic catch for holding

one part of the ram stationary until the other part has come into line therewith.

Referring to the accompanying sheet of 55 explanatory drawings:

Figure 1 is a sectional elevation illustrating one convenient application of the invention.

Fig. 2 is a sectional elevation on the line 60 AB of Fig. 1 and Fig. 3 is a sectional elevation on the line CD of Fig. 1.

The same reference letters in the three views indicate the same parts.

In the illustrated application of the invention for feeding coal or the like into a continuously operating horizontal or inclined retort, the ram or plunger for feeding the coal charge to the retort is divided into two parts, one part *a* (hereinafter termed 70 the upper part or the auxiliary ram) being directly connected by the rod *b* to the power actuating means, which may consist of a hydraulic motor, and serving to close the mouth of the coal chute or hopper *c* after 75 the charge has been received therefrom. The other and lower portion *d* of the ram (or what may be termed the main ram) is operated from the upper portion *a* when the acting faces of the two portions are in line 80 with one another, so that the two portions then move together. We provide on the main ram *d* a pivotally mounted catch piece *e* to hold such ram stationary until the upper portion or auxiliary ram *a* is about to 85 actuate the said main ram (due to the downwardly projecting part *f* of the upper or auxiliary ram engaging the cross member *g* of the lower or main ram), when the said catch *e* is released from the fixed hook *h* as 90 hereinafter described.

The operation of the charging means is as follows:—Assuming that the whole ram is in its rearmost position, as shown, coal can fall from the chute or hopper *c* in front of 95 the upper portion *a* and rest upon the top of the lower portion *d* of the ram: the upper portion *a* is then moved forward and pushes the coal off the lower portion into the space between the front face of the lower portion 100 and the material being carbonized in the retort *i*. This space is gradually filled in, the upper portion of the ram closing the mouth of the chute *c* and finally approaching with

its front face the position of the front face of the lower portion. The upper portion now releases the catch *e* (by the part *f* engaging the arm *j* of the catch) and finally 5 effects the propulsion of the lower portion, coal being forced forward by one or both portions of the ram according to the amount of the charge.

It will be understood that practically a 10 flat disk or block made up of pieces of coal is forced against the coal in the retort, so that an even pressure is applied thereto. If the coal charge is merely heaped up in front of the ram and compressed by the latter 15 there is excessive pressure exerted at the bottom of the charge in the retort which sets up wedging or binding and prevents the efficient operation of the plant. On the return stroke of the upper portion or auxiliary 20 ram *a*, the lower portion or main ram *d* may remain stationary until the upper portion has traversed a predetermined distance, when the two parts move together due to the part *f* of the upper portion *a* engaging the rear of 25 the lower portion *d* and finally the latter is locked by its catch piece *e*.

I may vary the details of my improved charging means to suit any particular requirements.

30 Having now described my invention,

what I claim as new and desire to secure by Letters Patent is:—

1. In charging devices for retorts, the combination with a main charging ram, of an auxiliary charging ram riding upon the 35 main ram, a chute delivering coal in advance of the auxiliary ram and upon the top of the main ram, means traversing the said auxiliary ram, and means for traversing the main ram from the auxiliary ram, the latter 40 in its movement closing the exit from the shoot, transferring the coal to the end face of the main ram and then carrying the latter forward with it to charge the retort, as set forth.

2. In charging devices for retorts, the combination with a main charging ram, of an auxiliary charging ram riding upon the main ram, a chute delivering coal in advance of the auxiliary ram and upon the top of 50 the main ram, means traversing the said auxiliary ram, means for locking the main ram against movement, means upon the auxiliary ram for releasing the locking means of the main ram and for traversing the latter with the auxiliary ram, as set forth.

In testimony whereof I have signed my name to this specification.

WILLIAM WILD.
